UNITED STATES PATENT OFFICE.

JAMES EDWARD POWELL, OF LITTLETON, COLORADO.

CYLINDER GRINDER.

REISSUED

Application filed March 21, 1922. Serial No. 545,557.

To all whom it may concern:

Be it known that JAMES EDWARD POWELL, citizen of the United States, residing at Littleton, in the county of Arapahoe and State of Colorado, has invented certain new and useful Improvements in Cylinder Grinders, of which the following is a specification, reference being had therein to the accompanying drawings.

The invention relates to cylinder grinders, and has for its object to provide a cylinder grinder comprising a plurality of circumferentially arranged and vertically disposed stone carrying members adapted to receive strips of abrasive material, preferably carborundum, said stone carrying members being pivotally connected at their upper and lower ends to plates carried by a vertically disposed shaft and are normally forced outwardly by springs. Also to provide the ends of the stone carrying members with arms having link connections with discs carried by a sleeve rotatably mounted on the shaft, and forming means for steadyng and bracing the stone carrying members and also forming means whereby the device may be used for grinding cylinder bores of different diameters.

With the above and other objects in view the invention resides in the combination and arrangement of parts as hereinafter set forth, shown in the drawings, described and claimed, it being understood that changes in the precise embodiment of the invention may be made within the scope of what is claimed without departing from the spirit of the invention.

In the drawings:

Figure 1 is a side elevation of the grinding device.

Figure 2 is a top elevation of the device showing the same disposed in a cylinder.

Figure 3 is a horizontal sectional view taken on line 3-3 of Figure 1.

Figure 4 is a sectional view through the upper end of the device, showing the same with the stone carrying members removed.

Figure 5 is a detail collective view of the parts of the device at one end of the device, showing the same in position for assembling.

Referring to the drawings, the numeral 1 designates the vertical shaft which is rotated in any suitable manner for revolving the device as a whole during a cylinder grinding operation. Rotatably mounted on the shaft 1 is a sleeve 2, which sleeve at its

upper and lower end terminates in horizontally disposed discs 3 and 4. The disc 3 is provided with radially disposed spaced recesses 5, and threaded on the outside of the disc 3 is a retaining ring 6, the purpose of which will presently appear. The lower disc 4 is provided with apertures 7, in axial alignment with the recesses 5. The recesses 5 and the apertures 7 receive the shafts 8 in links 9, which links are disposed on the out sides of discs 3 and 4. The other ends of the links 9 are provided with outwardly extending shafts 10, which are received in the apertures 11 of the arms 12, which are horizontally disposed and carried by the ends of the stone holding bars 13, which bars are in turn pivoted to discs 14, keyed at 15 to the upper and lower ends of the shaft 1, and held spaced from the discs 3 and 4 by means of the bosses 16 carried by the discs 3 and 4, which bosses extend outwardly. The arms 12 are pivoted to the discs 14 by means of inwardly extending cylindrical lugs 17, extending inwardly from the inner faces of the discs 14 and through the apertures 18 in the arms 12, therefore it will be seen that the stone carrying bars 13 may move inwardly and outwardly on their pivotal points formed by the cylindrical lugs 17 to accommodate the device to different diameters of cylinders. In use the device is rotated in the direction of the arrow *a* in Figure 2 and during the rotation the wall of the cylinder 19 will be ground by the carborundum stones 20, which have a dove tail connection 21 with the bars 13, and which are held against displacement by means of the set screws 22. During the rotation of the device the bars 13 are forced outwardly by means of coiled springs 23, one end of which springs engages over lugs 24 carried by the bars 13 and the other ends engage over removable lugs 25 carried by the sleeve 2, said springs being positioned preferably centrally of the device and radially disposed so that the maximum efficiency may be obtained as well as a compact structure. The springs exert an outward pressure upon the bars 13 and uniformly, thereby causing the carborundum members 20 to engage the wall of the cylinder 19 with uniform pressure and consequently insuring a uniform grinding of the cylinder. By providing the retaining ring 6, after the lower end of the device is assembled, the upper end can be

easily assembled and the lugs 8 of the links 9 at the upper end of the device may be passed into the recesses 5, and then the retaining ring 6 screwed on the disc 3 for holding said lugs against displacement.

It will be seen that the spring 23 will cause the device to accommodate itself to various sizes of cylinders and that when the bars 13 move outwardly the links 9 will 10 cause the sleeve 2 to rotate slightly according to the position of the bar, and not only bracing the bar but moving the discs 3 and 4, and consequently the sleeve 2 and the inner ends of the springs 23 to points where 15 they will exert a uniform pressure on the bars 13.

From the above it will be seen that a cylinder grinding device is provided, which is simple in construction, and one which 20 may be utilized for grinding cylinders of various diameters. It will also be seen that the grinding elements 20 may be easily and quickly removed and replaced if so desired.

25 The invention having been set forth what is claimed as new and useful is:

1. A cylinder grinder comprising a shaft, discs at the upper and lower ends of the shaft, inwardly extending lugs carried by 30 said discs, the lugs of each disc being in axial alignment, a plurality of spaced grinding element carrying bars in parallel relation to the shaft, said bars having right angled arms pivoted to the axially aligned lugs of the discs, a sleeve rotatably mounted on the shaft, the arms of said bars extending beyond their pivotal points, discs

carried by the sleeve, link connections between the ends of the arms of the bars and the sleeve carried discs and radially disposed springs interposed between the sleeve and the bars.

2. A cylinder grinder comprising a shaft, spaced discs carried adjacent the ends of the shaft, the outer discs being keyed to 45 the shaft, the inner discs being rotatably mounted on the shaft, the inner discs being connected together by a sleeve mounted on the shaft, grinder carrying bars in parallel relation to the shaft, inwardly extending arms carried by the bars and pivoted intermediate their ends to the outer discs, link connections between the inner ends of the arms and the inner discs, and radially disposed springs interposed between the bars 50 and the sleeve.

3. A cylinder grinder comprising a shaft, spaced discs adjacent the ends of said shaft, spaced bars in parallel relation to the shaft and pivoted to the outer disc, means for securing grinding elements in the bars, spring means for normally forcing said bars outwardly, link connections between arms of the bars and the inner discs, one of said inner discs being provided with a removable ring whereby the links may be connected to the discs and means whereby the inner discs will simultaneously rotate on the shaft to accommodate the springs to various sizes of cylinders.

In testimony whereof I hereunto affix my signature.

JAMES EDWARD POWELL.
